UNITED STATES PATENT OFFICE.

LOUIS K. LIGGETT, OF BROOKLINE, MASSACHUSETTS, ASSIGNOR TO
NATIONAL CIGAR STANDS COMPANY, OF JERSEY CITY, NEW JERSEY,
A CORPORATION OF NEW JERSEY.

DESIGN FOR AN ILLUMINATED CHANDELIER-SIGN.

No. 38,444.

Specification for Design.

Patented Feb. 12, 1907.

Application filed August 10, 1906. Serial No. 330,103. Term of patent 14 years.

To all whom it may concern:

Be it known that I, LOUIS K. LIGGETT, a citizen of the United States of America, residing in Brookline, county of Norfolk, State of Massachusetts, have invented a new, original, and ornamental design for Illuminated Chandelier-Signs, of which the following is a specification, reference being had to the accompanying drawing, forming part thereof.

The figure is a perspective view of a chandelier-sign, showing my new design.

I claim—

The ornamental design for an illuminated chandelier-sign, as shown.

LOUIS K. LIGGETT.
